UNITED STATES PATENT OFFICE.

JOHN C. SCHELTER, OF PITTSFORD, NEW YORK.

LAST.

Application filed June 4, 1921. Serial No. 475,062.

To all whom it may concern:

Be it known that I, JOHN C. SCHELTER, a citizen of the United States, and resident of Pittsford, in the county of Monroe and State of New York, have invented certain new and useful Improvements in Lasts, of which the following is a specification.

The present invention relates to lasts and more particularly to the type in which the last embodies two last parts movably connected together and secured in an expanded position by a lock or detent, an object of this invention being to provide a spring which acts to hold the detent both in locking and unlocking positions, provision being made for causing the spring to shift the detent toward locking position when the last is collapsed. Another object of the invention is to provide a spring for a locking detent which has a locking position and a pressure position the surface with which the spring engages in locking position being shiftable on the collapsing of the last to cause the spring to move automatically to pressure position. Still another object of the invention is to provide a bonding means rigidly secured to one of the last parts and movable on the other of the last parts, the bonding means having a portion with which the detent spring engages to lock the detent out of locking position, this portion being shifted relatively to the spring on collapsing of the last so that the detent is released to move to the detaining position. A still further object of the invention is to provide a locking detent and a bonding plate lying in the same plane, the detent being pivoted to one last part, and the bonding plate being rigidly secured to the other last part and having an abutment surface with which the detent engages to lock the last in an expanded position.

To these and other ends, the invention consists of certain parts and combination of parts, all of which will be hereinafter described, the novel features being pointed out in the appended claims.

In the drawings:

Fig. 1 is a sectional view through a last showing the latter locked in expanded position;

Fig. 2 shows the locking detent shifted and held away from locking position before the last is collapsed;

Fig. 3 is a detail view showing the manner in which the detent cooperates with the

bonding member to assist in shifting the spring to pressure position on the collapsing of the last;

Fig. 4 shows the manner in which the locking detent is released upon the collapsing of the last; and

Fig. 5 is a horizontal section on the line 5—5, Fig. 1.

Referring to the embodiment of the invention herein illustrated, 1 indicates the heel part of the last and 2 the toe part. These last parts are preferably pivotally connected through a pivot pin 3, which passes through the toe part 2 and also through a bonding member 4 which, in this instance, is in the form of a plate rigidly secured in a kerf 5 through pins 6 and projected into the kerf 7 of the toe part, the pivot pin 3 extending therethrough. The last parts have their opposed faces cut away to provide a space 8 above the pivot 3 so as to permit the collapsing of the last. The bonding member 4 preferably also serves as an abutment and to this end it is provided with a recess 9 forming a forwardly projecting portion 10 above said recess, the end 11 of said forwardly extending portion serving as the abutment.

With the end in view of locking the last in an expanded condition, there may be provided a lock or detent 12 which, in this instance, is pivoted in the kerf 7 of the toe part of the last on a pivot pin 13, said detent extending rearwardly from the pivot, so as to cooperate with the abutment 11. This detent is depressed downwardly out of engagement with the abutment and when the heel part is swung with reference to the toe part to collapse the last this detent enters the recess 9 below the projection 10 as shown in Fig. 4 of the drawings.

It is desirable in collapsible lasts with locking detents to provide some means for securing a detent out of locking relation with the abutment with which it cooperates to effect the locking action, and in this embodiment there is provided a spring 14 which is so mounted and constructed that, when the detent 12 is depressed or moved away from locking relation with its cooperating abutment, this spring will retain or hold the abutment out of such locking relation, provision being made whereby when the last is collapsed the spring will again be brought into action to exert pressure upon the detent in the direction to move the latter to

wards its cooperative relation with the abutment. In this embodiment of the invention the spring 14 is of a curved formation, being anchored at 15 to the detent 12 eccentrically to the axis of the latter. The free end of the spring cooperates with a part preferably carried by the heel part or part other than that on which the detent is mounted. In this instance, this part is in 10 the form of a nose or projection 16, the end of the spring which is curved at 17 when in operative position engaging the end on one side or surface of said nose or projection as shown in Fig. 1 so that the tension of the 15 spring tends to move the detent toward locking position. When the detent is depressed, as shown in Fig. 2, the curved end 17 rides to cooperate with the surface or side 18 of the projection and in this position binds 20 against said face or snaps behind the projection so that the detent is locked in its depressed position. This position is held until the last is collapsed when the surface 18 of the projection is forced against the spring 25 end 17 causing the latter to ride off the face 18 and onto the opposite side of the projection 16, as shown in Fig. 4. This shifting of the spring to pressure position is assisted by the engagement of the detent with a fixed 30 part on the last part on which the bonding member is rigidly secured. In this instance, the surface of the bonding member 4 is engaged by the under side of the detent as shown in Fig. 3 until the spring passes over 35 the point of the projection 16 when the spring shifts the detent to the position shown in Fig. 4. This prevents the breaking of the spring. In this position the spring again exerts pressure on the detent 40 and when the last is expanded the detent will move upwardly to cooperate with the abutment 11.

The operation of the invention will be understood from the foregoing but it may 45 be summarized as follows: Assuming that the parts are in the positions, as shown in Fig. 1, and it is desired to collapse the last; pressure is applied manually to the detent 12 to depress the latter or move it downwardly out of cooperation with the abutment 11. This carries the end 17 of the 50 spring into engagement with the shoulder or surface 18 of the projection 16 so that the spring interlocks with the bonding plate 55 and prevents the return movement of the detent. With the collapsing of the last the bonding plate 4 is forced against the spring end 17 in such a manner that the spring end rides off the face 18 onto the opposite side 60 of the projection 16 and in this position exerts pressure in a direction to move the detent into cooperative relation with the abutment. This occurs when the last is expanded.

55 From the foregoing it will be seen that

there is provided a last in which there is means for causing the action of the spring to cease when the lock or detent is moved to unlocking position, this means automatically causing said spring to become effective 70 to return the detent to locking position when the last is collapsed and then expanded. With this means there is arranged preferably a bonding member which has a surface forming an abutment engaging with the 75 spring which is shifted into such engagement when the lock or detent is depressed. This abutment on the bonding member cooperates with the spring when the last is collapsed to force said spring off said surface to a point on the bonding member where the spring action is again effective. It follows therefore that the bonding member has a locking surface and a pressure 80 surface, the spring being shifted to the 85 locking surface on the depression of the detent or lock and to the pressure surface on the collapsing of the last. The bonding plate which lies in a plane with the detent has an abutment with which the detent engages to lock the last in an expanded position.

What I claim as my invention and desire to secure by Letter Patent is:

1. In a last, a forepart and a heel part, 95 bonding mechanism uniting the said parts and arranged for relative movement of the parts to collapse the last, and a locking member mounted in one last part and engaging the other to hold the last in extended position, said locking member being arranged to be thrown out of locking position by the operator, and the bonding mechanism being constructed and arranged to push the locking member back toward locking position during the change in length of the last. 100

2. In a last, a forepart and a heel part, bonding mechanism uniting the said parts and arranged for relative movement of the parts to collapse the last, a locking member 110 mounted in one last part and engaging the other to hold the last in extended position, said locking member being arranged to be self locking out of locking position when thrown out of locking position by the operator, and the bonding mechanism being constructed and arranged to push the locking member back toward locking position during the change in length of the last. 115

3. In a collapsible last, a heel part, a forepart, a hinge member uniting said parts, and a locking member mounted in one part and abutting the other to hold the last extended, and arranged to be thrust toward the hinge member to move it from locking position, 120 the hinge member being arranged to move the locking member back toward locking position during the relative movement of the last parts. 125

4. In a collapsible last, a heel part, a fore- 130

part, a bonding member uniting said parts, and a locking member mounted in one part and abutting the other to hold the last extended, and arranged to be thrust toward the bonding member to move it from locking position, the bonding member being arranged to move the locking member back toward locking position during the relative movement of the last parts.

10 5. In a collapsible last, a heel part, a fore-part, a hinge member uniting said parts, and a locking member mounted in one part and abutting the other to hold the last extended, and arranged to be self locking when thrust toward the hinge member to move it from locking position, the hinge member being arranged to move the locking member back toward locking position during the relative movement of the last parts.

15 6. In a collapsible last, a locking member arranged to be self locking in inoperative position to permit collapse, and a swinging hinge member arranged to meet the

locking member during collapse to unlock the locking member from inoperative position. 25

7. A last comprising a fore part and a heel part divided by a cut providing a V shaped opening at the top, a bonding member pivotally connected with one of said parts, retaining means rigidly securing said bonding member in the other of said parts, an abutment rigid with said bonding member and separate from said retaining means, said abutment being exposed at the 35 V shaped opening, a detent exposed for manual operation at the V shaped opening, movably mounted on the said last part to which the bonding member is pivotally connected and arranged to cooperate with said abutment, and holding means for holding said detent out of cooperation with the abutment when the detent is shifted manually from such cooperation while the last is in an expanded condition. 40

JOHN C. SCHELTER.
